UNITED STATES PATENT OFFICE.

FERDINAND FRÉCHETTE, OF NOTRE DAME DE CHARNY, QUEBEC, CANADA.

GRATE-BAR.

1,224,159.

Specification of Letters Patent.

Patented May 1, 1917.

Application filed October 2, 1916. Serial No. 123,266.

To all whom it may concern:

Be it known that I, FERDINAND FRÉCHETTE, a subject of the King of Great Britain, residing at Notre Dame de Charny, Province of Quebec, Canada, have invented certain new and useful Improvements in Grate-Bars; and I do hereby declare that the following is a full, clear, and exact description of the invention, such as will enable others skilled in the art to which it appertains to make and use the same.

The present invention relates to grates and more particularly to that class of grate bars which are provided with water spaces 15 through which water may circulate to keep them cool and prevent warping and burning.

An object of the present invention is to provide hollow grate bars for furnaces and connect the same with a suitable source of 20 water supply whereby the water will be caused to circulate through the grate bars thereby cooling the grate bars and subsequently the water from the grate bars which has become heated may be discharged into 25 the boiler, thus heating the water previous to its discharge in the boiler and also protecting the grate bars by preventing them from becoming burned out.

A further object of the present invention 30 is to provide a system of the character specified for grate bars whereby should one or more of the bars of the grate become broken or in any other manner spring a leak so as to cause the water to discharge therefrom 35 the water supplied to the broken grate bar or bars may be disconnected so that a new grate bar or bars may be readily substituted therefor and the remaining grate bars may be continuously used.

40 With the above and other objects in view which will hereinafter appear as the description continues, the invention consists of the novel features of construction and the formation of parts as will be hereinafter more 45 fully described and particularly pointed out in the appended claims.

In the accompanying drawings is shown the simple and preferred form of the invention it being, however, understood that no 50 limitation is necessarily made to the precise structural details herein exhibited but the right is hereby reserved to any changes or alterations that may be had and come within the scope of the invention without departing 55 from the spirit thereof or sacrificing the efficiency of the same.

In the accompanying drawings;

Figure 1 is a diagrammatical representation of a furnace boiler showing the grate bars forming the subject matter of the present invention as in operative communication therewith by means of the system of water supply between the boiler and the grate bars; 60

Fig. 2 is a vertical section through one end of the grate bars in which the controlling valves are arranged; 65

Fig. 3 is an end elevation of the opposite ends of the grate bars;

Fig. 4 is a horizontal section taken on the line 4—4 of Fig. 2; 70

Fig. 5 is a plan view of the grate bars; and,

Fig. 6 is a vertical section through the same showing one of the bars of one section in elevation and one of the bars of the other section in vertical section. 75

Referring now more particularly to the drawings wherein like and corresponding parts are designated by similar reference characters throughout the several views. 80

The grate as herein shown comprises two sections indicated by the letters A and B and each section comprising a plurality of grate bars 1 cast or bored to form a longitudinal conduit 2 through which water may 85 pass freely, and in order to catch and direct the inrushing air beneath the grate so that it will evenly be distributed instead of rushing to the back and rising at one point, the bars are provided with the vane sections 90

3 which curve downwardly and forwardly toward the front end of the grate to deflect the air as it rushes into the ash pit beneath the grate. These vane sections are so disposed as to aline themselves to form substantially parallel vanes extending across the sides of the grate and running transversely of the grate bars. The adjacent ends of the grate bars are adapted to be mounted upon a support 4 and the alining grate bars of each section are in communication 100

by means of the couplings 5. The inner ends of the grate bars of section B are arranged upon the support 6 and these ends of the grate bars are connected by the U shaped couplings 7. The forward end of the grate bars arranged in section A are supported upon a casting 8 and this casting has a channelway 9 arranged therein. Leading 105 from the channelway 9 are a plurality of openings each of which corresponds with an opening in the forward end of the grate 110

bars, and arranged within these openings are the couplings 10 which form a means of communication between the various grate bars and the channelway 9, and these couplings are also each provided with right and left hand screw threads to form means of connection between the grate bars and the casting 8.

The boiler of the furnace indicated by the 10 numeral 11 is provided with a steam dome 12 and leading from the boiler are a pair of inlet pipes 13 and 14 each of which having a controlling valve 15 arranged therein and the ends of these pipes 13 are in communication with the opposite ends of the channelway 9 formed within the casting 8. Connected to the casting 8 and in communication with the channelway 9 at the point 16 is a supply pipe 17. Communicating 15 with the supply pipe 17 is a vertically extending pipe 18 and the latter being in communication with a horizontally arranged pipe 19 which leads from the boiler 11. Also leading from the pipe 19 is a vertical 20 pipe 20 which terminates in a coil 21 arranged within the tank 22. Leading from the bottom of the tank 22 is a pipe 23 which is also in communication with the supply pipe 17. The main water supply pipe 24 25 has arranged therein an injector 25, a controlling valve 26 and its upper end is in communication with the pipe 20 as at 27 which leads to the tank 22. Leading from the steam dome is a steam supplying pipe 28 and this pipe has arranged therein controlling valves 29 and is in communication 30 with the injector 25.

From the foregoing it is obvious that when the valves 29 are opened the steam from 40 the steam dome 12 will pass through the pipe 28 into the injector 25 where it will force the water from the main supply pipe 24 into the tank 22. The hot water from the boiler 11 will pass from the pipe 19 through the pipe 45 20 through the coils 54 into the tank 22 and this hot water will heat the tank to the required degree. As the cold water which is coming from the main water supply pipe is discharged within the tank 22 the hot water 50 coming from the boiler will heat the new supply of water within the tank 22 thereby supplying to the grate bars heated water of a temperature that will assist in cooling the grate bars without injuring the same. 55 Supported by means of a bracket 52 to the tank 22 is a casing 51 having a float valve 53 arranged therein. Leading to the casing 51 of the tank 22 is a supply pipe 50. As any or all of the steam that is liable to 60 accumulate within the tank 22 will pass into the tank 51 and permitted subsequently to be blown off pass by the float valve 53. The water contained within the tank 22 will obviously be governed by the height of the 65 water contained within the boiler 11.

Should one of the grate bars become worn or broken and a new one be desired to be substituted therefor I have provided a valve for controlling the entrance of water to each grate bar whereby the supply of water to each grate bar may be controlled and at the same time the circulation through the remaining grate bars will not be in any way affected. Arranged within the casting 8 are a plurality of valves 31 having valve stems 32, and these valves 31 are adapted to seat themselves in the valve seats 33 leading to the points of communication between the channelway 9 and the interior of the grate bars 1. From this it is obvious that should it be desired to discontinue the circulation of water through any one of the grate bars the valve controlling the admission to said grate bars may be caused to seat itself within the valve seats 33 thereby closing the means 75 of communication between the grate bars and the channelway 9. The valves 34 arranged at each side of the inlet openings 16 when in their lowermost position as shown 80 will open the means of communication to 90 the channelway 9 and the respective grate bars but should either one of these valves be closed half way one face thereof will close the channelway so as to prevent the flow of water therethrough at either side of these 95 valves and when they seat themselves within the valve seats 33 they will close the means of communication between the channelway 9 and the grate bars arranged above said valves. The valves 35 which are less in 100 length than the valves 34 are adapted to close the channelway 9 at the point 36 when raised so that when one face of the valves 35 will extend over the portions 36 of the channelway thereby permitting the circulation of 105 water through the grate bars arranged above the valves 35 but the remaining grate bars will be disconnected from the water supply. These valves 35 will also seat themselves in the valve seats 33 for disconnecting the 110 source of supply to the grate bars arranged above the valves 35 and when so arranged they will not interfere with the passage of water through the channelway 9 to the remaining grate bars. Likewise the remaining 115 valves may be used for disconnecting the supply of water to the grate bar arranged above said valve and also will break the means of communication between the main supply pipe of water and the remaining 120 grate bars arranged at the opposite sides of the valves by which the main supply of water is permitted to enter into the channelway 9.

From this it is obvious that the water admitted to enter through the port 16 into the channelway 9 will circulate through the channelway into the grate bars, through the grate bars in section A, through the connection 5, then into the grate bars arranged 130

within the section B, and subsequently be returned through the adjacent grate bars by passing through U shaped unions 7 and the water is subsequently carried off through the 5 pipes 13 and 14 to the boiler.

Having thus fully described my invention, what I claim as new and desire to secure by Letters Patent is:

1. In a grate of the character described 10 comprising two sections, grate bars arranged in each section, means of communication between one end of said grate bars, a casting having a channelway therein, an inlet pipe leading to the medial portion of said casting, outlet pipes leading from the opposite ends of said casting, means of communication between said channelway and said grate bars, valves for controlling the means of communication between said channelway and 15 20 said grate bars and said valves also adapted to close said channelway for the purpose set forth.

2. In a grate of the character described comprising two sections, a plurality of grate 25 bars arranged within each section, means of communication between the alining grate bars in each section, U shaped connecting unions between the rear ends of the grate bars in one section, a casting, means for supporting the forward end of the grate 30 bars in one section upon said casting, a channelway arranged within said casting,

means of communication between said channelway and the forward ends of the grate bars within one section, valve seats arranged 35 within said casting in the path of communication between said channelway and said grate bars, and vertically movable valves adapted to seat themselves in said valve seats and also adapted to close said channel- 40 way for the purpose set forth.

3. In a device of the character described the combination with a plurality of hollow interconnected grate bars, a casting for supporting one end of said grate bars, the said casting having a channelway formed therein and extending throughout its length, detachable means of communication between each of said grate bars and said channelway formed within said casting, inlet and outlet 50 55 openings communicating with said channelway, valve seats arranged within said casting, a valve adapted to rest within each of said valve seats, each of said valves adapted to close said valve seats for closing the means of communication between said channelway and said grate bars, and each of said valves adapted to close portions of said channelway substantially as and for the purpose 60 specified.

In witness whereof I have hereunto set my hand.

FERDINAND FRÉCHETTE.
